(57) **CLAIM**

The ornamental design for a tray, as shown and described.

DESCRIPTION

FIG. 1 is a front, top perspective view of a tray showing our new design;

FIG. 2 is a front view thereof;

FIG. 3 is a rear view thereof;

FIG. 4 is a right side view thereof, the left side view being a mirror image of the right side view;

FIG. 5 is a top view thereof; and,

FIG. 6 is a bottom view thereof.

The broken lines showing of a bottom rib represents unclaimed subject matter and forms no part of the claimed design.
